US00D875710S

(12) **United States Design Patent** (10) **Patent No.:** **US D875,710 S**
(45) **Date of Patent:** **** Feb. 18, 2020**

(54) **COMMUNICATIONS HEADSET OR HEADPHONE**

(71) Applicant: **Plantronics, Inc.**, Santa Cruz, CA (US)

(72) Inventors: **Chase Patrick Bailey**, Santa Cruz, CA (US); **Bowman Wang**, Ben Lomond, CA (US); **Matthew J Mainini**, Santa Cruz, CA (US)

(73) Assignee: **Plantronics, Inc.**, Santa Cruz, CA (US)

(**) Term: **15 Years**

(21) Appl. No.: **29/662,783**

(22) Filed: **Sep. 7, 2018**

(51) **LOC (12) Cl.** **14-01**

(52) **U.S. Cl.**

USPC **D14/205**

(58) **Field of Classification Search**

USPC D14/205, 223, 188, 192, 496; D24/174; 128/864, 865, 866; 181/129, 130, 135; 379/430, 431; 381/380, 381, 374; 455/90.3, 575.1, 569.1

CPC H04R 1/1033; H04R 1/10; H04R 25/00; H04R 1/1066; H04R 1/1016; H04R 5/033; H04R 5/0335

Primary Examiner — Paula Allen Greene

(57) **CLAIM**

The ornamental design for a communications headset or headphone, as shown and described.

DESCRIPTION

FIG. 1 is a left-front perspective view of a communications headset or headphone showing our new design;

FIG. 2 is a right-back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing the unclaimed features form no part of the claimed design.

1 Claim, 8 Drawing Sheets
